UNITED STATES PATENT OFFICE

SOL HOLSTEIN, OF NEW YORK, N. Y., ASSIGNOR TO STERLING BUTTON CO., INC., OF NEW YORK, N. Y., A CORPORATION OF NEW YORK

DESIGN FOR A BELT

Application filed August 18, 1932. Serial No. 44,627. Term of patent 3½ years.

To all whom it may concern:

Be it known that I, Sol Holstein, a citizen of the United States, and a resident of the city of New York, county of Queens, and State of New York, have invented a new, original, and ornamental Design for a Belt, of which the following is a specification, reference being had to the accompanying drawing forming a part thereof, wherein

Fig. 1 is a front elevational view of a belt embodying my new design; and

Fig. 2 is a plan view thereof.

The belt as a whole or contrasted parts thereof may be finished in noble metal or imitations thereof, or in other metal, or in color, or in combination of the foregoing, and may have either a dull or a high polish finish.

I claim:

The ornamental design for a belt or similar article substantially as shown and described.

SOL HOLSTEIN.
